L. FARR.

LIFE PRESERVER.

APPLICATION FILED JUNE 7, 1918.

1,288,857.

Patented Dec. 24, 1918.

ATTORNEY

UNITED STATES PATENT OFFICE.

LEWIS FARR, OF EL PORTAL, CALIFORNIA.

LIFE-PRESERVER.

1,288,857.

Specification of Letters Patent. Patented Dec. 24, 1918.

Application filed June 7, 1918. Serial No. 238,722.

To all whom it may concern:

Be it known that I, LEWIS FARR, a citizen of the United States, residing at El Portal, in the county of Mariposa and State 5 of California, have invented certain new and useful Improvements in Life-Preservers, of which the following is a specification.

This invention relates to life preservers, 10 and the object thereof is to provide a simply constructed buoyant device for supporting a person on the top of the water and for supplying air or oxygen for emergency use in case the wearer is submerged by under- 15 tow or other causes.

With the foregoing and other objects in view, which will appear as the description proceeds, the invention resides in the combination and arrangement of parts and in 20 the details of construction hereinafter described and claimed, it being understood that changes in the precise embodiment of the invention herein disclosed may be made within the scope of what is claimed without 25 departing from the spirit of the invention.

In the accompanying drawings:—.

Figure 1 represents a front elevation partly in section of a life preserver constructed in accordance with this invention, 30 parts being broken out for convenience in illustration.

Fig. 2 is a section taken on the line 2—2 of Fig. 1 and

Fig. 3 is a section taken at right angles 35 to that shown in Fig. 2 taken on the line 3—3 of Fig. 1.

In the embodiment illustrated, the preserver constituting this invention is composed of a plurality of closed cylinders 1, 40 any desired number of which may be employed, six being here shown. These cylinders are mounted on two spaced belts 2 and 3 having suitable means at their opposite ends for connecting them around the 45 waist of the user. These cylinders are preferably constructed of rubber, rubber cloth or other suitable air tight fabric and are connected midway their ends by tubes 4 preferably made integral therewith. Extending transversely of each cylinder 1 is a pipe section 5, the ends of which project into the tubes 4 at opposite sides of the cylinder as is shown clearly in Fig. 1, and each 50 of said pipe sections 5 has an opening 6 therein to afford communication with the interior of the cylinder. An air supply valve

7 is arranged at the end of the tube of the outermost cylinder as shown at the right of Fig. 1 and is designed for filling the cylinders by means of a pump such as is used in inflating pneumatic tires and the like. These cylinders 1 are designed to contain air or oxygen under pressure, said cylinders being preferably charged to about one-hundred pounds pressure, and the belt formed 60 thereby is designed to be secured around the waist of the user in the ordinary manner of a life preserver and operates not only as a buoyant device for supporting the weight of the user but as a container for supplying 65 air to the wearer when occasion demands as will be presently described.

Mounted adjacent each other on the belts 2 and 3 is a pressure reducing cylinder 8 and an exhalation chamber or cylinder 9, 75 said cylinders being of substantially the same size as the cylinders 1. These cylinders 8 and 9 have screw threaded plugs 10 and 10' for closing one end thereof, said plugs being shown threaded into the cylinders which are made of any suitable material.

This reducing cylinder 8 has a pressure reducing valve 11 mounted therein and a pipe 12 leading therefrom and equipped 85 with a stop cock 13 for turning on and cutting off air from the cylinder 8.

Mounted in the cylinder 8 are two compression chambers 29 which are rigidly connected with valve 11 and with the threaded 90 stem 30 and are united by a tubular coupling 31, all being supported in the screw plug 10.

The compression chambers 29 are composed of diaphragms 32 with concave faces 95 facing each other. While two of these chambers only are shown, it is to be understood that any desired number may be employed.

The valve 11 is composed of a tube with 100 openings 33 and 33^a spaced longitudinally from each other and closed by a plug 34, at its lower end. An L-shaped coupling or sleeve 35 is engaged with the tube 11 which slides in said sleeve and fits sufficiently close 105 to prevent the leakage of air between the two members. A groove or chamber 36 is formed in the member 35 and encircles the valve stem 11. This groove 36 and the opening 33^a in the tubular valve 11 are 110 placed in such relation to each other that when there is no pressure in cylinder 8 the

opening 33^a will register in groove 36 permitting the incoming air entering through tube 5 to pass into the groove 36 and thence through the hole or aperture 33^a into tube 11 and up through opening 33 in said tube into the cylinder 8. When the pressure in cylinder 8 is raised to a predetermined point, the compression chambers 29 are compressed and the tube 11 is thereby raised upward whereby the hole 33^a is placed out of register with the groove 36 thereby cutting off the air supply from tube 5.

To regulate the air pressure in cylinder 8 to any pressure desired, all that is necessary is to screw the tubular member 30 in or out thereby increasing or diminishing the pressure in cylinder 8.

From Fig. 1 of the drawings, and the description it will be obvious that when the pressure in cylinder 8 is increased it will compress the compression chambers 29 together and thereby shorten the valve stem 11 so that the aperture 33^a will be placed out of register with the groove 36 to cut off the air supply from tube 5. When the air pressure in cylinder 8 is reduced, the compression chambers 29 will expand thereby forcing valve stem 11 down and allowing the air to again enter the cylinder through tube 5.

30 The pipe 12 leads to a mouth piece 15 here shown in the form of a plate 16 having an extension 17 on its inner face, said extension having two longitudinally disposed bores 18 and 19 which communicate at their outer ends, one with the pipe 12 and the other with a pipe 14 which opens through the closure 10 of the exhalation cylinder 9. The extension 17 is also provided on its opposite face with notches 20 to receive the teeth of the user so that said mouth piece may be securely held for use. Attaching straps 21, preferably of elastic are also secured to the mouth piece and are designed to pass around the head of the user to assist 45 in retaining the mouth piece in operative position.

Arranged within the cylinder 9 is an exhaust pump 22, the plunger rod of which extends out through the closure 10 and is 50 equipped with a hand grip 23. This pump may be of any suitable or desired construction, and as here shown comprises a cylinder 24 having one end mounted in the closure 10 and depends into the cylinder 9 having an inwardly opening valve 25 at its lower end. A piston 26 operates on this cylinder 24 and is provided with the usual piston rod 27 on the outer end of which is mounted a handle 23.

60 A valve 28 is mounted in the pipe 14 adjacent the mouth piece, and opens outwardly permitting air to pass out from the pipe to the atmosphere and preventing the inlet of any air or water into the pipe.

65 In the use of this apparatus, the cylinders

1 having first been charged with oxygen or air, the belt is attached to the waist of the user, and if he finds that he is going to be drawn under water, the mouth piece 15 which has preferably been placed in operative position, when the preserver is attached around the waist, has the extension 17 thereof grasped firmly between his teeth, and at the same time, the stop cock 13 is opened, which will permit air or oxygen to pass 75 through the flexible tube 12 to the mouth piece 16 and into the lungs of the user. Exhalation takes place through valve 28 in the pipe 14 as long as the pressure of the water on the outside does not prevent the opening of the valve. In case the water pressure is sufficiently great as to prevent the opening of this valve 28 the air exhaled by the user will pass through the flexible tube 14 into the cylinder 9 and the user must operate the pump 22 to keep the pressure in cylinder 9 down to a comfortable breathing pressure.

A nose clamp must be used in connection with this device, and may be of any desired 90 or suitable construction to prevent water entering the nostrils. The use of such a clamp will force the wearer to breathe through the mouth.

The cylinders 1 may be of any suitable or 95 desired size, preferably about three or four inches in diameter by eight inches in length, and a number of these cylinders would of course afford considerable buoyancy and insure the support of the wearer.

The pressure regulating valve 11 must be sufficiently sensitive to retain the air at constant pressure, which pressure must be determined by experiments.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the claimed invention.

Having thus fully described my invention, what I claim as new and desire to secure by 115 Letters Patent, is:—

1. In an apparatus of the class described, an air container, a mouth piece, tubes leading from said mouth piece, an exhaust valve in one of said tubes and a cut-off valve in 120 the other, a pressure reducing cylinder communicating with said container and with one of said tubes, and a pump carrying cylinder connected with the other tube.

2. In an apparatus of the class described, 125 a plurality of parallel spaced belts, air containers carried thereby, tubes connecting said containers, a mouthpiece, tubes leading therefrom, an exhaust valve in one of said tubes and a cut off valve in the other, a

pressure reducing cylinder communicating with one of said containers, and with one of said tubes, and a pump carrying cylinder connected with the other tube.

- 5 3. A life preserver comprising an air container, a mouth-piece, a plate having a projection extending at right angles therefrom and provided with longitudinal bores, tubes communicating with said bores, an exhaust valve in one of said tubes and a cut off valve

in the other, a chamber communicating with the tube having the exhaust valve, a suction pump for said chamber, and an air supply connected with the other tube.

In testimony whereof I affix my signature 15
in presence of two witnesses.

LEWIS FARR.
